UNITED STATES PATENT OFFICE.

WILBER N. BAILEY, OF BAY CITY, MICHIGAN.

TRACE-FASTENING.

SPECIFICATION forming part of Letters Patent No. 380,160, dated March 27, 1888.

Application filed September 16, 1887. Serial No. 249,865. (No model.)

To all whom it may concern:

Be it known that I, WILBER N. BAILEY, a citizen of the United States, residing at Bay City, in the county of Bay and State of Michigan, have invented certain new and useful Improvements in Adjustable Trace-Fastenings, of which the following is a specification, reference being had therein to the accompanying drawings.

10 This invention relates to new and useful improvements in adjustable trace-fastenings; and the invention consists in the peculiar construction of the whiffletree and trace, as more fully hereinafter described, and shown in the accompanying drawings, in which—

Figure 1 is a perspective view of one end of a whiffletree with the trace engaging therewith, said trace being shown detached to show the construction of the parts. Fig. 2 is a horizontal section of Fig. 1 with the trace secured to the whiffletree.

A is the whiffletree. B is a guide-loop. C is a guide-flange on the rear side of the whiffletree. D is one of the traces. E is a stud secured to the trace, and G is a slotted metallic strap secured upon the rear side of the whiffletree. The other end of the whiffletree (not shown) is constructed precisely the same.

The whiffletree A may be of any suitable description. The guide-loop B is preferably formed integrally with a socket, by means of which it may be readily secured upon the ends of a wooden whiffletree, and the guide-flange C may also be formed integrally therewith on the upper or lower side.

35 The strap or plate G may run the whole length of the whiffletree, or there may be a separate plate for each end, as thought best. It is secured to the rear side of the whiffletree in any suitable manner, and contains a series of adjusting-slots, a, enlarged at their inner ends to engage and disengage the stud E in the well-known manner.

The stud E consists, preferably, of a round 45 flat-headed rivet, the trace resting on a shoul-

der on the rivet to form a neck, c, on the stud, which prevents the latter from binding or playing too loosely in the slots. The outside washer, b, is secured to the trace by rivet-heading the outer end of the stud. At the bottom of the slots a a recess is formed to admit the head of the stud, and this recess may be formed either on the whiffletree or on the inside of the metallic strap G.

The operation of the device is very simple, 55 and is accomplished by passing the trace through the guide-loop on the end of the whiffletree and under the guide-flange C, and then engaging the stud G into that one of the slots a which gives the desired length of trace. By 60 pulling on the trace in front of the guide-loop the stud will then slip forward and take firm hold in the slot.

To prevent the trace from being cut out, the outer end of the socket F is rounded, as shown. 65

The advantages of my improved trace-fastening are that the whole strength of the trace is preserved, at the same time the whiffletree is strengthened by the metallic strap, and may thereby be strengthened to any desired degree; further, the traces are upheld and prevented from flapping around. A large degree of adjustability may be obtained in the length of the trace. Instead of the guide-loop B any other suitable guide may be substituted for 75 the trace.

What I claim as my invention is—

As an improved article of manufacture, the metallic strap G, comprising in a single element the strap part or plate, a socket, F, having rounded corner, a guide-loop, B, and an overhanging guide-flange, C, and the whole adapted to serve as set forth.

In testimony whereof I affix my signature, in presence of two witnesses, this 26th day of August, 1887.

WILBER N. BAILEY.
